UNITED STATES PATENT OFFICE.

JOHAN M. ANDERSEN, OF BOSTON, MASSACHUSETTS, ASSIGNOR TO ALBERT AND J. M. ANDERSON MANUFACTURING COMPANY, OF BOSTON, MASSACHUSETTS, A CORPORATION OF MAINE.

CIRCUIT-CONTROLLER.

1,178,121.

Specification of Letters Patent.

Patented Apr. 4, 1916.

Application filed February 25, 1914. Serial No. 821,083.

To all whom it may concern:

Be it known that I, JOHAN M. ANDERSEN, a citizen of the United States, residing in Boston, county of Suffolk, and State of Massachusetts, have invented an Improvement in Circuit-Controllers, of which the following description, in connection with the accompanying drawings, is a specification, like characters on the drawings representing like 10 parts.

This invention relates to an electric circuit controller comprising coöperating contact members, one of which is movable with relation to the other and has a sliding engagement therewith.

The present invention has for its object to provide an electric circuit controller of this character with a tapering resistance, which is metallic and substantially great and 20 which is electrically and mechanically connected with one of the said contact members and coöperates with the other member to have a sliding engagement therewith, so as to be gradually introduced into and cut out 25 from the electric circuit as will be described.

The invention is especially adapted among other uses, to be embodied in an end cell switch, and particularly an end cell switch of the character shown and described in U. 30 S. Patent No. 996960 granted to me July 4, 1911, wherein a movable contact member co- 35 operates with a plurality of stationary contact members arranged in substantially the same plane, and with which the movable contact member has a sliding engagement and serves to cut into or out of the electric circuit, one or more storage battery cells. The tapering metallic resistance may be attached to the movable contact member, and 40 be moved with the latter over the stationary contact members, or as is preferred in the construction of end cell switch shown in the patent, the tapering metallic resistance may be attached to each of the stationary, 45 contact members.

The metallic tapering resistance consists of a plurality of thin metallic members or leaves, which are spaced apart and arranged with one edge in substantially the plane of 50 one surface of the stationary contact member and are electrically separated for a portion of their length and are electrically connected

with the stationary contact member to form a tapering resistance, which is gradually introduced into and cut out of the circuit, to 55 avoid injurious sparking and short circuiting of the battery cells, as the latter are introduced into and cut out of the main circuit, as will be described.

These and other features of this invention 60 will be pointed out in the claims at the end of this specification.

Figure 1 is a plan view of a sufficient portion of an end cell switch provided with a circuit controller embodying this invention 65 to enable it to be understood, and Fig. 2, a sectional view on an enlarged scale of one of the main contact members or terminals shown in Fig. 1 and the metallic resistance secured thereto, the section being taken in a 70 horizontal plane parallel with the upper surface of the main contact member.

Referring to the drawings, I have shown in Fig. 1, a portion of an end cell switch substantially such as shown and described 75 in the patent referred to, in which the bars 1 to 13 represent the connections leading to storage battery cells (not shown) and said connections have terminals 14, which are of substantial width and each of which forms 80 a main contact member, with which coöperates a movable contact member 15, which also makes contact with a bus bar 16. The movable contact member 15 is capable of being moved in opposite directions from one 85 terminal to another after the manner described in the patent referred to, but inasmuch as the mechanism by which the contact member 15 is moved, constitutes no part of the present invention, it need not be specifically described herein as it is fully set forth 90 in the patent referred to.

The main contact members or terminals 14 for the end cells are spaced apart, and each is provided with one or more tapering 95 metallic resistances 20, the terminals for the end cell connections 1 and 13 being each provided with a single resistance 20, and the terminals of the intermediate cell connections being provided with two resistances, 100 one on each side thereof. In the present instance, I have shown one construction of tapering metallic resistance, which I prefer for use with the end cell switch herein shown.

Each resistance 20 is preferably made as herein shown, see Fig. 2, and consists of a long metal strip 21 of material width and preferably of a high resistance metal, such as German silver, which is bent to form a substantially large number of folds or leaves 22, constituting auxiliary contact members, and each preferably of a length substantially equal to the length of the main contact member or circuit terminal 14. The auxiliary contact members or leaves are assembled in substantially close proximity to one another, with their edges approximately in the planes of the upper and lower surfaces of the terminal 14, and are separated electrically from one another for a portion of their length by layers 23 of insulating material, such as fish paper, but which may be of other insulating material.

The folded metal strip 21 is provided at the end adjacent the circuit terminal, with one or more folds, which are separated by wider spaces than the spaces which separate the folds of the said strip remote from the circuit terminal. In the present instance the strip 21 is provided with two substantially wide spaces, one being formed between the first two folds or auxiliary members marked 30, 31 and the other between the third and fourth folds marked 32, 33. The space between the first two folds 30, 31 is filled with metal strips of different conductivity than that of the long German silver strip, and in the present instance said space has located in it a single strip 40 of copper, and a strip 41 of German silver, which is provided with three folds or leaves, which also constitute auxiliary members, two of which marked 45, 46 are located in the space between the folds 30, 31, and the third fold of which, marked 47, is located in the space between the third and fourth folds 32, 33, of the long strip 21.

The folds 45, 46 form a space in which is located a metal strip preferably of copper, which is bent to form two folds or auxiliary members marked 50, 51 which terminate in said space. These various folds are electrically separated between their ends by strips 23 of insulation, such for instance as fish paper; and at one end, the strips marked 30, 40, 45, 50 are electrically connected with one another and with the circuit terminal 14, by short pieces or strips 60 of metal preferably copper, which extend but partially the length of the folds with which they make metallic contact. The folds or leaves of the various strips may be secured to the side of the terminal 14 in any suitable manner, and are herein shown as secured by screws 62, which extend through holes in an outside plate or clamping bar 63 and through openings in the various members or folds of the resistance and into threaded sockets in plugs or nuts 64, which are located in suitable holes in the circuit terminal 14, said nuts be-

ing insulated from said terminal by bushings 65 of insulating material, and said screws being insulated from the folded strips of the metallic resistance by bushings 66 of insulating material.

It will be understood that the folded metal strips are applied to the side of the circuit terminal, preferably with the upper and lower edges of the folds in the planes of the upper and lower surfaces of the terminal, so as to form continuations of said surfaces.

In practice it is preferred to make the resistance 20 of such width, that the space between the end of the resistance on one terminal and the next adjacent terminal is less than the width of the movable contact member 15, so that the latter in its movement may be engaged with one terminal and with the resistance of the next adjacent terminal, and on the further movement of the contact member from the terminal 14 of one connection as 7 toward the terminal 14 of the connection 6, the resistance 20 of the terminal of connection 7 is gradually introduced into the circuit of said connection, and the resistance 20 of the terminal of connection 6 is gradually cut out of the circuit of connection 6.

At a point midway between the terminals 95 of the connections 7, 6, the movable contact member 15 engages both resistances, and on further movement engages the terminal of connection 6 before it leaves the resistance attached to the terminal of connection 7. As 100 a result the amperage of the current between adjacent terminals is reduced to a substantially small amperage by the large amount of resistance, and sparking or arcing between the movable contact member and stationary 105 contact member or terminal which it leaves, is avoided or at least reduced to a point where it is negligible and not injurious.

By reference to Fig. 2, it will be observed that the folds or leaves of the various strips forming the resistance, practically constitute auxiliary contact members which are thin and which are electrically separated for the greater portion of their length, yet are electrically connected at their ends, so that, as 110 the contact member 15 slides across the edges of the thin leaves or auxiliary contact members, the resistance is gradually introduced into or cut out from the circuit. In the present instance, the auxiliary contact members are shown as substantially parallel and in close proximity to one another, and while this construction is especially adapted for use where a space of minimum width between the terminals is available, as in the 115 end cell switch herein shown, it is not desired to limit the invention to this particular construction, as the auxiliary members may be otherwise spaced apart.

In the present instance, the tapering me- 130

tallic resistance is shown as secured to the stationary terminals, but it is not desired to limit the invention in this respect.

The circuit controller of the end cell switch herein shown, is designed to handle very large currents as for instance as great as 40,000 amperes, and it will readily be understood, that sparking or arcing between the movable member 15 and the stationary members or terminals 14 would under such circumstances be very disastrous if permitted to occur.

The main contact members are made of substantial width so as to carry the large current, and to avoid the disastrous sparking or short circuiting between adjacent terminals or contact members, a tapering metallic resistance is employed which is attached to one of the main contact members to move therewith and to have a sliding engagement with the coöperating main contact member. In the construction of metallic resistance herein shown, a two fold tapering effect is obtained, one due to the continuous strip 21 and the other to the auxiliary metal strips located near the main contact member or terminal. The auxiliary strips which form part of the tapering metallic resistance, also have the function of avoiding an arc being formed when the movable contact member passes from the main contact member onto the resistance.

It is preferred to employ the auxiliary strips when a current of large amperage is to be handled or when more than one battery cell is placed in series between adjacent connections, but in other conditions the auxiliary strips may be dispensed with and the single long strip depended upon to obtain the tapering resistance desired. By means of the metallic resistance, the latter wears evenly with the main contact or terminal and any desired resistance within limits

may be obtained, and a maximum resistance can be located in narrow space.

45

Claims:

1. In a circuit controller in combination, a contact member, and a resistance attached to said member and comprising a metal strip provided with a plurality of folds, some of which are separated by spaces of different widths, auxiliary metal strips located in the wider of said spaces and provided with folds, and insulation between the folds of said metal strips.

55

2. In a circuit controller, in combination, a main contact member, a plurality of substantially thin auxiliary contact members arranged side by side with their edges substantially in the plane of a surface of the main contact member and electrically separated from one another for a portion of their length and electrically connected with the main contact member to form a tapering resistance, some of the said members adjacent to said main contact member having interposed between them both metal members and insulating members.

65

3. A metallic resistance comprising a plurality of substantially thin members arranged with their edges in substantially the same plane and some of which are separated by spaces wider than others, auxiliary members located in the wider of said spaces, and means for electrically separating said members for a portion of their length, and means for electrically connecting said members to form a tapering resistance.

70

In testimony whereof, I have signed my name to this specification in the presence of two subscribing witnesses.
